UNITED STATES PATENT OFFICE.

WILLIAM W. ALLEN AND JAMES W. ALLEN, OF CORNELL, ILLINOIS.

RAILROAD-GATE.

SPECIFICATION forming part of Letters Patent No. 694,815, dated March 4, 1902.

Application filed May 9, 1901. Serial No. 59,469. (No model.)

To all whom it may concern:

Be it known that we, WILLIAM W. ALLEN and JAMES W. ALLEN, citizens of the United States, residing at Cornell, in the county of 5 Livingston and State of Illinois, have invented certain new and useful Improvements in Railroad-Gates; and we do hereby declare the following to be a full, clear, and exact description of the invention, such as will enable others 10 skilled in the art to which it appertains to make and use the same.

This invention relates to automatic crossing-gates, the object in view being to provide one or more gates at a grade-crossing adjacent to a railway having combined therewith operating mechanism adapted to be located at any desired distance from the gate or gates and arranged to be actuated by a train moving in either direction, so as to automatically 20 close or open the gate or gates.

The automatic crossing-gate contemplated in this invention may be used at points where vehicle-roadways cross railways or may be used at the crossings of intersecting railways, 25 so that a train moving on either road and in either direction will automatically close the gates which cross the intersecting road. The gate and the operating mechanism therefor may also be utilized on farms and in various 30 other places where it is desired to have a vehicle automatically open and close the gate without the necessity of the driver's dismounting.

With the above general objects in view 35 the invention consists in the novel construction, combination, and arrangement of parts hereinafter fully set forth, illustrated, and claimed.

In the accompanying drawings, Figure 1 is 40 a perspective view showing a crossing with a pair of gates mounted adjacent thereto and showing the mechanism for automatically opening and closing the gates. Fig. 2 is an enlarged side elevation showing the frame of 45 the gateway, one of the gates, and a portion of the operating mechanism. Fig. 3 is a vertical section taken in line with the vertical shafts at one side of the crossing. Fig. 4 is a bottom plan view of the road-bed adjacent 50 to the gates, showing the arrangement of operating-cables. Fig. 5 is a vertical section taken at right angles to Fig. 2 and in line with

oppositely-located vertical shafts. Fig. 6 is a cross-section through one of the traveler-guideways, showing the traveler mounted 55 therein. Fig. 7 is a detail perspective view of the traveler. Fig. 8 is a longitudinal section through the traveler and guideway, showing the latches for locking the traveler-arm and the means for tripping said latches at 60 opposite ends of the throw of the traveler. Fig. 9 is a perspective view of the traveler-arm. Fig. 10 is a longitudinal section through the traveler-arm, showing the sliding member and actuating-springs therefor. Fig. 11 65 is a detail perspective view of the sliding member of the traveler-arm. Fig. 12 is a vertical sectional view of a single gate provided with counterbalance-weights and especially designed for use where a single gate only is 70 employed. Fig. 13 is a plan view showing the manner of equipping intersecting railways with automatic gates constructed in accordance with this invention.

Similar numerals of reference designate 75 corresponding parts in all figures of the drawings.

In order to illustrate the application of the automatic crossing-gate to a railway, we have shown a portion of a railway-bed, (indicated 80 at 1,) and an intersecting vehicle-roadway 2, crossing the railway at grade. In order to provide for mounting and properly guiding the gates, we employ a pair of upright frames, one of such frames being mounted at each 85 side of the railway, as clearly shown in Fig. 1, and each frame consisting of a pair of posts or uprights 3, arranged at a suitable distance apart to enable one or more teams to pass between them. The posts or uprights 3 are 90 firmly connected at their lower ends to cross bars or ties 4, which extend beneath the rails of the railway and are in turn connected by tie-bars or stringers 5, extending longitudinally of the railway, the frame thus constructed being covered by a platform 6, the upper surface of which is approximately flush with the tops or heads of the rails, as is customary at crossings of the kind referred to. Each pair of posts or uprights is connected at the 95 top by horizontal overhead frame-bars 7, which form bearings for the upper ends of a pair of vertical shafts 8, arranged adjacent to the posts 3 and having their lower ends

mounted in bearings in the platform 6 and stringers 5, while said shafts are also provided with bearings intermediate their ends formed in brackets 9, connected to the posts 5. In order to prevent vehicles from striking against the vertical shafts 8, guards 10 extend upward from the platform 6, said guards being preferably semicylindrical in shape, so as partially to embrace the shafts at their inner adjacent sides.

Each of the vertical shafts 8 is provided at its lower end with a small drum 11, which will hereinafter be termed the "lower" drum. The drums 11 are located beneath the platform 6 and have wound thereon a pair of traveler-cables 12, which are connected at their ends to a pair of travelers, hereinafter described, and which are mounted between the rails of the railway, so as to be operated 15 by a train moving in either direction. Located about centrally between the rails and also between the lower drums of oppositely-located vertical shafts are what may be termed "main" drums 13, around which the traveler- 20 cables also pass in passing to and from and around the lower drums on the gate-operating shafts. In order that the operation of the gate-operating shafts 8 may be understood, before proceeding farther the reeving of the 25 travelers will now be traced. Beginning with one of the travelers 14, one of the traveler-cables 12, which is connected thereto, extends therefrom beneath the platform 6 past the first or adjacent main drum 13 to the farther main 30 drum, around which it is wrapped one or more times. The cable then extends laterally and passes one or more times around the lower drum of one of the vertical shafts, thence across the main drum to the opposite side, 35 where it passes one or more times around the lower drum of the oppositely-located vertical shaft, thence back to the main drum, around which it is wrapped one or more times. The cable thence extends outward toward the 40 other traveler 14 and to the farther end of the guideway in which the traveler moves, where the cable passes around a guide-pulley 15, journaled in a bracket connected with the guideway, and thence to the outer end of the 45 traveler or that end which is farthest from the crossing. Another traveler-cable connects with the opposite or inner end of the traveler just referred to, passes beneath the platform 6 to the farther main drum, is then 50 wrapped around said drum and reeved around the lower drums of the vertical shafts in the same manner as previously described in connection with the first cable, afterward passing outward from beneath the platform 55 around a similar guide-pulley 15 at the farther end of the traveler-guideway, and being finally secured to the outer or farther end of the first traveler. It will be understood that as one traveler is moved lengthwise of its 60 guideway by a moving train the other traveler is drawn in the opposite direction by means of the traveler-cables, and at the same

time all of the vertical gate-operating shafts are simultaneously and equally revolved in the same direction.

The posts or uprights 3 are provided with vertical guides 16, behind which are slidably received the end portions of a pair of gates 17 in the form of bars adapted to slide up and down between the guides and posts, the said 75 gate-bars being provided with pins 18, extending through them and forming stops to prevent displacement of the gate from the guides. Connected with each of the gate-bars is a pair of gate-operating cables or bands 80 19, which extend upward from the gate-bars over guides 20 and thence around upper drums 21 on the gate-operating shafts 8, the last-named drums being arranged, preferably, beneath the connecting top bars 7. The 85 opposite portions of the gate-operating cables extend downward from the gate, passing through openings in the platform and over guides 22, after which they are wrapped around and connected with the lower drums 90 11. In view of this arrangement it will now be seen that as the shafts are rotated in one direction the upper portions of the operating-cables will be wound upon the upper drums simultaneously with their unwinding from the 95 lower drums, thereby elevating the gate-bar. When the direction of rotation of the shafts is reversed, the gate-operating cables are unwound from the upper drums and wound upon the lower drums, thereby moving the gate-bars downward. It will thus be understood 100 that the operation of raising and lowering the gates is entirely automatic and controlled by the travelers 14 as they are slid in their guideways by a train moving in either direction.

The travelers 14 may be located at any desired distance from the crossing, and each of said travelers comprises a frame consisting, preferably, of parallel spaced plates 23, suitably bolted or otherwise fastened together. The said traveler-frame is also preferably provided at both ends with oppositely-located 110 wheels or rollers 24, which roll upon a base-plate or bed-piece 25, extending lengthwise of the road-bed between the rails and fastened for convenience to the ties. Upon the base-plate 25 is mounted a guideway consisting of parallel strips or rails 26, having overhanging and inwardly-projecting flanges 27, beneath 115 which the rollers 24 of the traveler are confined, thus preventing the traveler from escaping from the guideway.

Mounted centrally of the traveler is a traveler-arm 28, the same being intermediately fulcrumed between a pair of ears 29 on the frame-plates of the traveler. The upper portion of the traveler-arm extends a sufficient distance above the surface of the road-bed to be struck by the pilot-board or cow-catcher of the engine for causing the traveler to move in one direction or the other, according to the direction in which the train is moving. The lower end of the arm extends between the frame-

plates of the traveler and is provided with a terminal lip or projection 30, which is alternately engaged with and disengaged from corresponding notches 31 in the inner adjacent ends of a pair of latches 32, the same being fulcrumed between their ends upon pins connecting the side plates of the traveler, while the outward and oppositely-projecting arms of the latches are rounded on their under sides, as shown at 33, and adapted to come in contact with trips or cams 34, arranged at or near the opposite ends of the guideway. The trips or cams 34 operate to vibrate the latches one at a time, and thereby unlock and release the lower end of the traveler-arm, so that the upper end thereof may swing in the direction in which the train is moving, so as to fold downward and allow the train to pass over it. The traveler-arm is, however, held locked in its vertical position until the traveler reaches the end of the guideway, at which time the gates are either wholly opened or closed, as the case may be. As soon as the traveler-arm is tripped the traveler stops, the train no longer having any effect thereon. As soon as the traveler-arm is released by the train after it has passed the said arm is returned to its vertical operative position by means of a double-acting spring 35, comprising oppositely-located coils 36, which are wound in the same direction around the oppositely-projecting portions 37 of the pin or rod 43, which forms the fulcrum for the traveler-arm, the extremities of said pin or rod being bent at an angle to receive the looped extremities 39 of the spring, which partially encircle said extremities from opposite sides. The coils are united by a central connecting portion 40, which is connected with the traveler-arm, preferably by passing the same through an opening 41 in said arm, as shown. The construction of spring described enables the traveler-arm to be vibrated in either direction when released by the latches and serves by its tension to return said arm to its normal, vertical, and operative position. When the arm is thrown downward in one direction, it acts to wind up one of the coils of the spring, while when it is vibrated in the opposite direction it acts to wind up the other coil. It will also be seen that by the arrangement described the traveler-arm in winding up one of the coils will not unwind the other coil, as on account of the fact that the outer end of the coil is not held fast when turning in one direction the coil as a whole will turn bodily and altogether upon the fulcrum pin or rod. In this way no reverse tension is put upon either of the coils of the spring, and the life of the spring is thereby greatly increased.

Under some conditions it may be desirable to throw the gate-operating mechanism out of gear, so that it will not be operated by moving trains, and, in order to accomplish this we provide one or both of the latches of each traveler with handles 42, connected pivotally at their lower ends to the latches and

provided at their upper ends with laterally-projecting lips or extensions 43 for enabling the handles to be operated, the said extensions also preventing the handles from falling and becoming wedged between the latches and frame of the traveler. The operator by lifting the handles elevates the outer ends of the latches, and by then throwing the handles over the connecting bolts or pins of the traveler-frame the latches will be held elevated and inoperative, so that the traveler-arm being unlocked may be drawn downward in either direction by the train without imparting any movement to the travelers and gates.

In order to prevent injury to the traveler-arm when struck by a moving train, said arm is made telescopic, comprising a hollow body 85 or hinged member 44 and a spring-pressed slide or sliding member 45, which is pressed outward through the outer end of the hollow body by means of one or more springs 46, arranged in the channeled side portions of the 90 hollow body, the said springs being properly seated at one end, while their opposite ends are brought to bear against laterally-projecting pins or shoulders 47 on the sliding member 45, as clearly shown in the drawings. The 95 sliding member is made of sufficient breadth to insure the proper engagement between it and the point of the pilot-board or cow-catcher, thereby preventing the pilot-board from bearing against one side of the traveler-arm and bending the same over laterally, which would probably render the gate-operating mechanism inoperative. By arranging the sliding member so as to telescope within the main body of the traveler-arm should the 100 traveler-arm be inclined toward an approaching train the sliding member will be pressed downward into the main body of the traveler-arm without causing injury thereto, and the same operation will be produced by projections pendent from the bottoms of cars drawn by the train, preventing injury to such parts of the cars and also to the traveler-arm. The outwardly-projecting portion of the sliding member 45 is preferably recessed or cut away, 105 as shown at 48, to provide yielding wings 49, between which is interposed a cushioning-spring 50, which yieldingly supports the wings of the sliding member and better adapts said member to take the concussion produced by 110 the sudden blow imparted thereto by a rapidly-moving train. The construction just described also prevents the liability of fracturing or bending the outwardly-projecting portion of the sliding member when a sudden 115 blow is struck thereon.

From the foregoing description it will be seen that the gates are entirely automatic in operation and that they are opened and closed by a train moving in either direction, obviating the necessity of employing a gateman at each crossing. Where a series of crossings occur at short intervals, the several gates may be coupled to the same pair of travelers, so

that they will all be simultaneously opened and closed. Where gates are erected at a surface crossing of intersecting railways, the construction hereinabove described may be duplicated, so that each of the railways will be equipped with a pair of gates, whereby a train moving on one track will close and open the gates of the intersecting track.

If desired, the travelers and guideways therefor may be provided with contact plates or buttons arranged in an electrical circuit with alarm mechanism and an electric-lighting system, so that the approach of a train may be signalized at the crossing by electric lights and the ringing of an audible alarm, such as a gong or a bell. Such electrical connections may be of the usual type and may be readily applied by any one skilled in the art.

In erecting a gate for farm purposes it is only necessary to employ a single gate, and therefore one pair of vertical gate-operating shafts may be dispensed with. In connection with farm-gates it is desirable to employ counter-balance-weights for the gate on account of the size and weight of the gate which must necessarily be employed in order to fence off stock. We therefore extend vertical guides 51 at one side of the posts or uprights 3, which guides are preferably in the form of rods. Upon such guides are arranged sliding weights 52, having connected thereto cables 53, which extend upward over suitable guides 54 and thence downward, where they connect with the gate. The weights serve to counterbalance the gate, and thus relieve the mechanism for operating it. The arms of the travelers may be arranged to be struck either by the wheels of the vehicle approaching the gate or departing therefrom or by a portion of the running-gear of the vehicle, as may be preferred.

It will thus be seen that the invention is susceptible of considerable change in the form, proportion, and minor details of construction, and we therefore reserve the right to make such changes as properly fall within the scope of the appended claims.

Having thus described the invention, what is claimed as new, and desired to be secured by Letters Patent, is—

1. In an automatic crossing-gate, the combination with a gate, of means for opening and closing the same comprising a sliding traveler, operative connections between the traveler and gate, a guideway for the traveler, a folding arm carried by the traveler, a latch for locking said arm in its operative position, and a trip located in the guideway and adapted to operate upon the latch for throwing the latter out of engagement with the folding arm.

2. In an automatic crossing-gate, the combination with a gate, of means for opening and closing the same comprising a sliding traveler, operative connections between the traveler and gate, a folding arm carried by the traveler, latches for holding said arm in its operative position, trips arranged at opposite ends of the throw of the traveler for moving the

latches and releasing the traveler-arm, and a spring for returning the traveler-arm to its operative position.

3. In an automatic crossing-gate, the combination with a movable gate, of means for opening and closing the same comprising a sliding traveler, operative connections between the traveler and gate, a guideway in which the traveler moves, a folding arm carried by the traveler, means for automatically locking and tripping said arm, and a sustaining-spring for said arm comprising a pair of coils, one of which acts to move the arm in one direction, the other coil acting to move the arm in the opposite direction.

4. In an automatic crossing-gate, the combination with a movable gate, of means for opening and closing the same comprising a sliding traveler, operative connections between the traveler and gate, and a traveler-arm having telescopic members.

5. In an automatic crossing-gate, the combination with a movable gate, of means for opening and closing the same comprising a sliding traveler, operative connections between the traveler and gate, and a traveler-arm having telescopic members one of which is pivotally connected with the traveler.

6. In an automatic crossing-gate, the combination with a movable gate, of means for opening and closing the same comprising a sliding traveler, operative connections between the traveler and gate, and a pivoted and folding traveler-arm connected with the carriage and embodying a hollow body, a telescopic member slidably mounted therein, and means for normally pressing the telescopic member outward.

7. In an automatic crossing-gate, the combination with a movable gate, of means for opening and closing the gate, comprising a sliding traveler, operative connections between the traveler and gate, and a traveler-arm embodying a hollow body pivotally connected with the traveler-frame, a sliding member arranged to telescope within the hollow body and provided with shoulders, and springs arranged within channeled portions of said body and exerting a pressure against the shoulders of the sliding member.

8. In an automatic crossing-gate, the combination with a movable gate, of means for opening and closing the gate comprising a sliding traveler, operative connections between the traveler and gate, and a traveler-arm embodying a sliding telescopic member provided with wings spaced apart and having a cushioning-spring interposed between the wings.

9. In an automatic crossing-gate, the combination with a movable gate, of means for opening and closing the gate comprising a sliding traveler, operative connections between the traveler and gate, a folding traveler-arm connected with the traveler and having a projection or shoulder, a latch pivotally mounted in the traveler-frame and hav-

ing a notch for engagement with the projection on the traveler-arm, and a trip arranged in the path of the traveler and adapted to operate upon the latch for releasing the traveler-arm and allowing the same to fold.

5 10. In an automatic crossing-gate, the combination with a vertically-movable gate, of parallel shafts each provided with a pair of drums, gate-operating cables connected with the gate and wound upon said drums, and means actuated by a moving object for imparting simultaneous rotation to said shafts.

11. In an automatic crossing-gate, the combination with a vertically-movable gate, of parallel shafts each provided with a pair of drums, separate gate-operating cables for each shaft, each cable being connected with the gate and having its opposite ends wound upon the drums of its respective shaft, and means operated by a moving object for simultaneously rotating said shafts.

12. In an automatic crossing-gate, the combination with a vertically-movable gate, of parallel vertical shafts arranged at opposite sides of the gateway and provided with drums, gate-operating cables connected with the gate and wound upon said drums, and means operated by a moving object for imparting simultaneous rotation to said shafts.

13. In an automatic crossing-gate, the combination with a vertically-movable gate, of parallel vertical shafts at opposite sides of the gateway, gate-operating cables connected with said shafts and gate, sliding travelers arranged at opposite sides of the roadway protected by the gate, and operative connec-

tions between said travelers and shafts for imparting rotary movement simultaneously to said shafts.

14. In an automatic crossing-gate, the combination with a pair of gates, of sets of parallel shafts arranged contiguous thereto, drums actuated by said shafts and carrying gate-operating cables which act to raise and lower the gates, and means for simultaneously rotating all of the shafts comprising sliding travelers arranged at opposite sides of the crossing, and cables connected with the travelers and passing around drums on the gate-operating shafts, substantially as described.

15. In an automatic crossing-gate the combination with a pair of vertically-movable gates, of sets of vertical gate-operating shafts having drums, gate-operating cables wound upon said drums, and means for simultaneously rotating the shafts consisting of sliding travelers arranged at opposite sides of the crossing, a pair of main drums interposed between drums on the lower ends of the gate-operating shafts, and cables connected with the travelers and passing around the main drums and also around the drums on the lower ends of the gate-operating shafts, substantially as and for the purpose specified.

In testimony whereof we affix our signatures in presence of two witnesses.
